UNITED STATES PATENT OFFICE.

JOHN WOCK, OF CANTON, OHIO, ASSIGNOR TO THE CANTON STEEL ROOFING COMPANY, OF SAME PLACE.

EAVES-TROUGH.

SPECIFICATION forming part of Letters Patent No. 415,854, dated November 26, 1889.

Application filed June 17, 1889. Serial No. 314,665. (No model.)

To all whom it may concern:

Be it known that I, JOHN WOCK, a citizen of the United States, residing at Canton, in the county of Stark and State of Ohio, have 5 invented certain new and useful Improvements in Eaves-Troughs; and I do hereby declare that the following is a full, clear, and exact description of the same, reference being had to the annexed drawings, making a 10 part of this specification, and to the letters of reference marked thereon, in which—

Figure 1 is a view of a portion of a sheet from which the joint is formed. Fig. 2 is a 15 view showing the joint formed and a portion 15 of the roll or bead broken away. Fig. 3 is a transverse section through line 2 2, Fig. 2.

The present invention has relation to eaves-troughs; and it consists in the different parts and combination of parts hereinafter 20 described, and particularly pointed out in the claim.

Similar letters of reference indicate corresponding parts in all the figures of the drawings.

25 In the accompanying drawings, A represents the sheet from which the trough proper is formed. One end of the sheet A is provided with the narrowed portion B, which is of the form shown in Fig. 1, and is for the 30 purpose of forming the groove a. The groove a is formed by first bending the portion B back against the sheet A, and again bending a part of said portion against itself, thereby

forming the groove a. The last bend of the portion B is made at a point so as to bring 35 the raw end of said portion B a short distance past the first bend, as shown at b, Fig. 2, and is for the purpose of forming a guide to enter the end of a section of a trough.

For the purpose of preventing the portion 40 B from spreading apart after the joint a is formed, the extension C is provided, which extension is embraced by the roll or bead D.

It will be seen that by my peculiar construction I am enabled to form the joint without the 45 use of solder, and at the same time produce a perfect water-tight joint, and one that will not be liable to become disconnected.

Having fully described my invention, what I claim as new, and desire to secure by Letters 50 Patent, is—

The combination of the sheet A, provided with the narrowed portion B, having the extension C, the groove a, formed by bending the narrowed portion B against the sheet A 55 and a part of said narrowed portion against itself at a point to form the guide, as at b, substantially as and for the purpose specified.

In testimony that I claim the above I have hereunto subscribed my name in the presence 60 of two witnesses.

JOHN WOCK.
